UNITED STATES PATENT OFFICE

EDWARD A. WERNER, OF ATLANTA, GEORGIA

METHOD OF JOINING DISSIMILAR BODIES

Application filed March 5, 1928. Serial No. 259,316.

This invention relates to a method of permanently joining dissimilar bodies having different coefficients of expansion and contraction under the same prevailing conditions.

The particular adaptation of the invention which forms the subject matter of this application is the formation of a permanent joint between a slab of marble, granite or similar material and a body of wood or like substance.

A joint made in accordance with the principles of my invention will permit of the relatively uneven expansion and contraction of bodies of the characters above noted without destroying or injuriously affecting the permanency of the joint; will render the construction fireproof; and will be insoluble in and impervious to water, alcohol, acids, alkalies and other chemical solvents, thus assuring its permanency against any and all of usually destructive agencies.

The single figure of the drawing illustrates, more or less diagrammatically, a joint between a slab of marble and a body of wood.

In the drawing the slab of marble, or its equivalent, is illustrated at 1, and a body of wood, or its equivalent, is illustrated at 2.

Obviously marble and wood possess different coefficients of expansion or contraction under a prevailing condition common to both and in order to successfully join two such materials in a permanent manner, the joint formed between the two must have a fair degree of elasticity.

In forming such a joint in accordance with the principles of my invention the body of wood is thoroughly dried by any well known means. Preferably one of the well known hard woods is employed.

On the surface of the wood body to which it is desired to attach the marble slab, I first spread a coating of organic (animal) glue of a relatively high grade, which is indicated at 3. Upon this glue coating 3, I place a sheet of asbestos, indicated at 4. This assemblage is then placed in a suitable press or clamp and pressure applied thereby to cause the asbestos sheet to uniformly adhere to the wood. While under this pressure the assemblage is

subjected to a temperature of 130° C., to superdry the glue and thereby make it moisture-proof. After heating to the above temperature, the glue will be insoluble, thus assuring a permanent joint between the wood and the sheet of asbestos.

The face of the slab of marble which is to be secured to the asbestos sheet is preferably rubbed to form a relatively smooth surface, and to this rubbed surface I apply a coating of shellac varnish 5 made of "bleached" shellac.

The wood and asbestos assemblage is then removed from the press, and while still warm the slab of marble is applied thereto with the shellac coating in contact with the asbestos sheet, as shown. The shellac will cause the marble slab to adhere to the asbestos sheet, and the heat previously applied to the wood and asbestos assemblage and still retained therein will cause the bleached shellac to gradually change its composition to a state wherein it becomes insoluble in water, alcohol, acids and alkalies.

If desired the entire assemblage may then be subjected to additional heat to thoroughly dry the joint, which will then become permanent and will not be affected by any of the elements or conditions above noted.

The asbestos sheet imposed between and permanently attached to the wood and marble bodies lends to the joint the necessary elasticity which permits the relatively uneven expansion and contraction of these bodies under a prevailing condition, and furthermore makes the construction fireproof.

The structure thus provided has a wide scope of utility and may be successfully employed in building construction as a wainscoting or panel, in which the marble slab may be relatively thin, permitting the use of expensive marble which would otherwise be prohibitive for general use as a wainscoting or for similar decorative purposes.

The construction may also be successfully employed in the construction of various forms of monuments, supplanting the solid blocks of ornamental stone by a substantial wooden framework faced with a relatively thin slab of the ornamental stone, thus permitting

shipment of a comparatively large monument a greater distance for a cost equal to cost of shipping a small solid monument a relatively shorter distance, and making the erection of such monuments considerably easier.

5 While I have described the use of certain specific materials throughout the specification, obvious equivalents for these materials may be substituted without departing from 10 the spirit of the invention, however, a joint employing the organic glue, the bleached shellac and the sheet of relatively tough and elastic material imposed between the bodies to be joined has proven to be both practical 15 and efficient, when the joint is formed by the process above described and which I claim as new in the art.

I claim:

1. A method of joining a body of wood 20 with a body of stone comprising the coating of one surface of the wood with an animal-organic glue, applying a sheet of asbestos to the coated surface, simultaneously pressing and heating the assemblage to superdry the 25 glue, applying a coating of shellac to one surface of the stone, releasing the pressure on said assemblage and applying the coated surface of the stone to the exposed surface of the asbestos sheet while the preheated assemblage is still warm whereby the shellac 30 is changed from a liquid to a solid insoluble mass.

2. A method of joining a body of wood with a body of stone comprising the coating 35 of one surface of the wood with an animal-organic glue, applying a sheet of asbestos to the coated surface, simultaneously pressing and heating the assemblage to superdry the glue, applying a coating of shellac to one 40 surface of the stone, releasing the pressure on said assemblage and applying the coated surface of the stone to the exposed surface of the asbestos sheet while the preheated assemblage is still warm whereby the shellac 45 is changed from a liquid to a solid insoluble mass, and reheating the entire assemblage to thoroughly dry the joint.

3. An article of manufacture comprising a body of wood, a body of stone, a relatively 50 yieldable body comprising an asbestos sheet superimposed between adjacently positioned faces of said wooden and stone bodies, a body of animal organic glue superimposed between the face of the wooden body and the adjacent 55 face of the asbestos sheet, and a body of shellac superimposed between the opposite face of said asbestos sheet and the adjacent face of said stone body.

EDWARD A. WERNER.
